UNITED STATES PATENT OFFICE.

IRA ROBBINS, OF CAMDEN, NEW JERSEY, ASSIGNOR TO TIMOTHY D. KELLY,
OF PHILADELPHIA, PENNSYLVANIA.

ELECTRIC SWITCH.

SPECIFICATION forming part of Letters Patent No. 642,159, dated January 30, 1900.

Application filed May 26, 1899. Serial No. 718,318. (No model.)

To all whom it may concern:

Be it known that I, IRA ROBBINS, a citizen of the United States, residing at Camden, in the county of Camden and State of New Jersey, have invented certain new and useful Improvements in Electric Switches; and I do hereby declare the following to be a full, clear, and exact description of the invention, such as will enable others skilled in the art to which it appertains to make and use the same.

This invention relates to certain new and useful improvements in electric switches of that class designed to be operated by means of contacts carried by the trolley or trolley-pole and engaging contacts at predetermined points to actuate the tongue of the switch through suitable intermediate electrical connections.

The present invention has for its objects, among others, to improve upon this class of devices, whereby greater efficiency and simplicity of construction are attained and the mechanism better adapted for operation in either direction of movement of the car or trolley. I provide the trolley-pole with swinging weighted levers or contacts free to swing in either direction and normally held in their vertical position without the employment of springs. Upon the car are foot-levers adapted to be operated by the foot of the motor-man to throw the current into one or the other of the two contacts, so as to energize the required one of two magnets or solenoids to throw the switch in the desired direction. I aim, further, at improvements in the details of construction, all as more fully hereinafter described, shown in the drawings, and then particularly pointed out in the appended claims.

The invention is clearly illustrated in the accompanying drawings, which, with the letters of reference marked thereon, form a part of this specification, and in which—

Figure 1 is an elevation showing the overhead portion of my invention. Fig. 2 is a plan of the overhead contacts. Fig. 3 is an enlarged sectional view on the line 33 of Fig. 1. Fig. 4 is a diagrammatic view of the entire mechanism. Fig. 5 is an enlarged section through the foot-lever and its coöperating contact.

Like letters and figures of reference indicate like parts throughout the several views.

Referring now to the details of the drawings by letter, A designates the trolley-wire, 55 B the trolley, and C the trolley-pole, mounted in the usual manner.

D is a sleeve mounted on and insulated from the trolley-pole near its upper end, and projecting from diametrically opposite sides 60 thereof are the pins or studs d, insulated from each other, upon each of which is mounted to freely swing an arm E, extending above and below the pivot, the upper end being of such length as to engage the fixed contact herein- 65 after described and the lower portion weighted, as seen at e, to normally hold the arm in its vertical position, as seen in Fig. 1.

F are hangers suspended in any suitable manner and supporting the trolley-wire, and 70 in these hangers are supported the transverse rods G, around which are insulating-sleeves g, and from these rods are suspended the hangers H, which at their lower ends carry the contact-plates I, which may be of any de- 75 sired length, and their ends are preferably turned up, as seen at i, so as to prevent injury to the swinging arms as they come in contact therewith.

J is the tongue of the switch. It is pivoted 80 at j, as seen in Fig. 4, and has pivotally connected therewith, as at k, one end of the rod K, the other end of which is pivotally connected, as at l, with the free end of the pivoted armature L, which is disposed between 85 the two magnets M and N, which are disposed beneath the surface of the ground in a watertight box at any convenient place.

The contacts L may be placed at any convenient distance from the switch, it being 90 understood that they are entirely insulated from the trolley-wire, and the magnets are energized by the trolley-current through the medium of these contacts in the following manner:

Mounted on the front and rear platforms of the car are the foot-levers or switches O O and P P, as indicated in Fig. 4. A common connection or wire 1 unites all of the switches with the trolley-pole, the latter being hollow, 100 as seen in Fig. 3, and the wire passing therethrough.

2 and 3 are wires passed through the trolley-pole, as seen in Fig. 3, and connected one to each of the swinging arms or contacts E and with the free poles o and p of the foot-levers 5 or switches O and P.

The free ends of the magnets are connected together and a connection 4 joins them with the rails or ground-return circuit, as seen in Fig. 4.

10 One of the contacts I is connected by wire 5 with the magnet M, while the other of said contacts is connected by wire 6 with the other magnet N, all as shown clearly in Fig. 4.

15 R are springs around the shanks of the foot-levers and the free poles, as seen in Fig. 5, for normally keeping the same in their relative positions.

20 With the parts constructed and arranged substantially as above set forth the operation will be apparent, and, briefly stated, is as follows: When the trolley-pole nears the contacts I, the upper ends of the contacts E, being in their vertical position, will strike the under sides of the said contacts I, and by reason

25 of their being pivoted they will assume an inclined position, so as to maintain a rubbing contact with the contacts I. Before reaching the said contacts I the motorman by placing his foot upon one or the other of the foot-levers completes the circuit through either of

30 the contacts E, and hence through the corresponding contact I, so as to throw the switch in the desired direction. As the contacts E come to the end of the contacts I they will suddenly leave the same by reason of their free-swinging motion and the weights at the lower ends thereof. This sudden breaking of the contact is considered important, as it will prevent destructive sparking at the contacts.

35 40 As the circuit is completed the magnet M or the magnet N, according to which of the contacts E is thrown into the circuit, is energized and the armature attracted thereby, so as to move the rod K, and thereby the switch J, as will be readily understood.

45 The free-swinging movement of the contacts E permits of their being employed as well in the one direction of movement of the car as in the other.

50 It is evident that the mechanism above described may be employed under ground as well as overhead and that other modifications in detail may be resorted to without departing from the spirit of the invention or

55 sacrificing any of its advantages, and I therefore do not wish to restrict myself to the precise details of construction herein shown and described.

What is claimed as new is—

1. The combination with a pivoted switch, 60 the trolley-wire and the fixed contacts, of a trolley and its pole, swinging weighted contacts on said pole independent of the trolley, and electrical devices and connections for actuating said switch, substantially as specified. 65

2. The combination with a pivoted switch, the trolley-wire and the fixed contacts, of the trolley, its hollow pole, swinging weighted contacts independent of the trolley, on the pole, a pivoted armature, magnet and connections between said armature and switch, and wires connected with each swinging contact and passed through the pole and connected with said magnet, substantially as specified. 70

75 3. The combination with the trolley-wire and the fixed contacts insulated therefrom, of the trolley, its pole, the swinging contacts thereon on pivots out of line with the axis of the trolley, foot-levers and contacts, a switch 80 and electric devices and connections for actuating the same, substantially as specified.

4. A hollow trolley-pole, a sleeve thereon, laterally-projecting studs on said sleeve independent of and out of line with the axis of the trolley and projecting beyond the sleeve, and weighted contacts pivotally mounted on said studs, substantially as specified. 85

5. A hollow trolley-pole, a sleeve thereon with laterally-projecting studs, between the 90 axis of the trolley and the other end of said pole, weighted arms pivotally mounted on said studs, wires running through the pole and connected with the said arms, a main wire connected with the pole, a pivoted switch, 95 and foot-levers or switches and their contacts and electrical connections substantially as specified.

6. The combination of a pivoted switch, magnets, an armature disposed between the 100 same, a connection between the free end of the armature and the switch, fixed contacts connected with the magnets, a trolley-pole, weighted swinging contacts thereon upon opposite sides of the pole out of line with the 105 axis of the trolley, foot-levers and contacts, a main-line wire connected with the pole and with the said levers, and wires connecting the swinging contacts with the contacts of the foot-levers, substantially as specified. 110

In testimony whereof I affix my signature in presence of two witnesses.

IRA ROBBINS.
